Primary Examiner — Jennifer L Watkins

(74) Attorney, Agent, or Firm — Thomas|Horstemeyer,
LLP(57) **CLAIM**

The ornamental design for shoe, as shown and described.

DESCRIPTION

1.1 is a perspective view of a shoe, showing my new design;

1.2 is a right side view thereof;

1.3 is a left side view thereof;

1.4 is a front view thereof; and

1.5 is a rear view thereof.

The broken lines shown in the drawings of the shoe represent stitching and form part of the claimed design.
